Application June 24, 1946, Serial No. 678,766
In Sweden March 31, 1944

15 Claims. (Cl. 202—12)

1
This invention relates to the dry distillation of solid fuel in ovens of the type discussed in the pending application of David Dalin and Claes Joel Gejrot, Serial No. 581,700, filed March 8, 1945.

In apparatus of this type solid fuel such as oil-bearing shale, coal, or wood is fed in pieces of convenient size through an upright distillation retort in a furnace for discharge from the open bottom of the retort onto a fuel bed where the residue coke is burned. The hot combustion gases emanating from the fuel bed and continuously withdrawn from the furnace are utilized to heat the fuel traveling through the retort to effect pre-heating followed by degassing of the fuel and distillation of the gases. Distillation gases produced in the retort are continuously withdrawn by means of a duct having its mouth opening to the interior of the retort in the zone at which distillation takes place but near the bottom of the distillation zone.

Hence, the speed with which the distillation process can be carried out depends upon the degree of heat developed by burning of the fuel and applied to the retort to effect degassing and distillation of the fuel therein.

This would seem to indicate that high combustion rates would produce correspondingly high rates of distillation of the fuel and this is true except for the fact that most fuels suitable for dry distilling sinter at relatively low temperatures and high temperatures must, therefore, be avoided to preclude waste of the fuel and even complete stoppage of the distillation process.

To preclude sintering it has been customary in the past to control the temperature of the fuel bed by forcing excess quantities of air through the fuel bed from beneath or to inject large quantities of steam or inert gas onto the fuel bed all for the purpose of maintaining the fuel bed beneath sintering temperatures.

While it was possible to cool the fuel bed and avoid sintering by these past expedients, distillation was not speeded but was, in fact, retarded. This follows from the fact that the produced combustion gas was low in carbon dioxide (CO₂) content seldom above 5% while having high content of excess air, steam or inert gases. This, of course, resulted in excessively large quantities of combustion gases and precluded the combustion gases from attaining the maximum temperatures obtainable under an optimum of combustion conditions, and consequently the distillation process was slower as a result thereof.

Moreover, cooling of the fire bed in this manner has resulted in extensive waste of heat.

2
In the dry distillation of fuel, it is, of course, necessary to draw off the combustion and distillation gases separately without allowing admixture thereof. This was to some extent accomplished in the process of the aforementioned application, Serial No. 581,700, by vertical adjustment of the mouth of the distillation gas withdrawal duct within the retort to locate the same a distance above a zone of substantial balance between the pressures of the combustion and distillation gases, and thus definitely above the area of zero pressure differential therebetween.

The location of the zero pressure differential area within the retort is capable of wide variation, however, since it is a function of the size of the fuel pieces being processed, and the relationship between the sub-atmospheric pressures of the distillation and combustion gases.

Hence, it was frequently necessary to adjust the position of the withdrawal duct lengthwise of the retort in accordance with change in the location of the area of substantially zero pressure differential therein so as to avoid admixture of combustion gases with the distillation gases being withdrawn from the retort, and the retorts had to be of substantial height to enable such adjustment without interfering with preheating, degassing, and distillation of the fuel therein prior to its passage out of the distillation zone and before reaching said area of substantially zero pressure differential.

It will also be seen that the location of said area of zero pressure differential within the retorts of past distilling apparatus depended to a certain extent upon the rate of combustion of the fuel as controlled by excess quantities of air, steam, or inert gas.

Normal combustion depends upon the quantity of air supplied from beneath the fuel bed, the characteristics of the fuel being burned, and the resistance which a bed of such fuel offers to the flow of air for combustion therethrough. The use of relatively small size fuel pieces would seem desirable from the standpoint of speeding distillation by reason of their ability to burn at a faster rate than larger pieces, but they have the disadvantage of causing more rapid sintering of the fuel and offering increased resistance to the flow of air through a bed of such fuel making it difficult to cool the fire bed by excesses of air in the conventional manner.

Hence, relatively small size fuel pieces were avoided in past distillation processes and apparatus, and the rate at which distillation was carried out was limited not only for this reason, but

also because of the use of steam, air, or inert gases to prevent sintering of the fuel as hereinbefore brought out.

The main object of the present invention resides in the provision of a dry distillation process of the character described by which distillation is effected in considerably less time than was heretofore possible so as to enable greatly increased production.

More specifically it is an object of this invention to provide a process for dry distilling relatively small size fuel pieces which are capable of being burned faster to speed distillation, and to provide for removal of sufficient heat from a burning bed of such fuel pieces as to effectively prevent sintering of the fuel without incurring all of the objections inherent in the use of excess air, steam or inert gas for this purpose.

It is another object of this invention to provide a distillation process of the character described in which the differential in pressure above and beneath the fuel bed is maintained at a value which produces the maximum rate of combustion and makes possible utilization to the fullest extent of the heat energy available in the fuel.

It has been seen that a measure of control of the temperature of the fuel bed to prevent sintering has been obtained by flowing considerable excesses of air through the fuel bed, or by injecting steam or inert gas onto the fuel bed, but such cooling of the fuel bed only leads to retarding production and waste of heat.

As stated previously, it is one of the objects of the distillation process of this invention to cool the fuel bed without producing any change in combustion gas analysis from that resulting from combustion under optimum conditions whereby the combustion gases may be utilized to better advantage for preheating, degassing, and distillation of the fuel passing through the retort to speed the distillation process.

In this respect, it is another object of this invention to provide a dry distillation apparatus of the character described with heat absorbing and dissipating ducts extending through the fuel bed and through which a heat absorbing fluid is adapted to be circulated to carry off sufficient heat from the interior of the fuel bed to prevent sintering of the fuel and thus enable combustion at maximum rates.

This method of cooling the fuel bed makes possible utilization of the excess heat absorbed from the fuel bed for useful steam generating purposes.

The excess heat to which the lower portion of the retort was subjected in the past has necessitated the use of costly heat resisting alloys in the construction of the retort. In this respect it is another object of this invention to provide for cooling of the lower end portion of the retort subjected to the intense heat of the burning fuel directly therebeneath by fluid cooled ducts in contact with the walls of the retort so as to prevent overheating thereof and to allow the retort to be made from ordinary and less expensive metals.

In any distillation apparatus of the character described it is essential that the distillation gas produced within the retort of the furnace be withdrawn from above a neutral zone separating the distillation and combustion zones and within which is an area where the differential in pressure between the distillation and combustion gases is zero, to prevent admixture of combus-

tion gas with the distillation gas and vice versa.

The location of this area of zero pressure differential tends to vary in accordance with the pressure differential above and below the fuel bed, the temperature of the combustion gases and to a certain extent in accordance with the size of the fuel pieces being treated.

In order to increase the rate of production and improve combustion, retorts and furnaces of great height have been employed in the past to thereby lengthen the processing zone and allow the location of the area of zero pressure differential to vary. Optimum results as regards the production rate and combustion conditions have, however, not been attained or even approached by these past methods because they entailed the maintenance of temperatures low enough to prevent disruption of the distillation and degassing processes and sintering of the fuel being burned. Only by slow combustion, an excess of air, steam or inert gases for cooling purposes and retorts and furnaces of great height has it been possible to process this type of fuel.

It is another object of this invention, therefore, to provide an improved distillation apparatus of considerably less height than was heretofore possible.

To achieve this purpose, it is another object of this invention to provide a distillation apparatus of the character described in which the combustion and distillation gas pressures are continuously compared and balanced against each other to at all times maintain said area of zero pressure differential at a fixed elevation spaced beneath the distillation zone and above the fuel bed but preferably close thereto so as to permit reduction in the overall height of the apparatus.

By controlling the differential of the combustion and distillation gas pressures in this manner and by cooling the fuel bed internally in the manner stated so as to avoid the objectionable consequences of using excess air for this purpose, it is possible to reach distillation efficiencies heretofore unattainable.

With the above and other objects in view which will appear as the description proceeds, this invention resides in the novel application of the method and procedure and in the construction, combination and arrangements of parts substantially as hereinafter described and more particularly defined by the appended claims, it being understood that such changes in the precise embodiment of the herein disclosed invention may be made as come within the scope of the claims.

The accompanying drawings illustrate several complete examples of the physical embodiments of the invention constructed in accordance with the best modes so far devised for the practical application of the principles thereof, and in which:

Figure 1 is a diagrammatic longitudinal cross sectional view through the dry distillation apparatus of this invention;

Figure 2 is a cross sectional view through the furnace of Figure 1 taken on the plane of the line 2-2;

Figure 3 is a plan view of a dry distilling installation employing batteries of furnaces connected with common combustion and distillation gas withdrawal ducts;

Figure 4 is a fragmentary cross sectional view illustrating a modified furnace construction employed when the units are to be arranged in batteries;

Figure 5 is a fragmentary detail perspective view illustrating a portion of the cooling means for the fuel bed;

Figure 6 is a fragmentary perspective view illustrating a modified type of cooling element for the fuel bed;

Figure 7 is a fragmentary cross sectional view through a furnace illustrating the retort provided with means to improve heat transfer from the hot combustion gases flowing over its exterior walls to the fuel pieces passing through the interior of the retort; and

Figure 8 is a detail view of a portion of the distillation gas withdrawal duct.

Referring now more particularly to the accompanying drawings in which like numerals indicate like parts, the numeral 10 generally designates the distillation oven or furnace of this invention. The furnace comprises an elongated upright shaft 11 of substantially rectangular cross section, and having its walls lined with a refractory material (not shown) in the conventional manner to withstand high temperatures.

A grate structure generally indicated by the numeral 12 is provided in the bottom portion of the furnace to support a bed 13 of fuel thereon to enable the fuel to be burned in the customary manner. The fuel which may comprise coal, wood or oil bearing shale broken up into relatively small particles is fed into the furnace through one or more upright distillation retorts 14 extending down into the furnace toward the grate structure 12 but with their bottom ends opening to the interior of the furnace at a point spaced above the grates to define the depth of the fuel bed which extends between the bottom ends of the retorts and the grate structure.

The upper ends of the retorts project upwardly through a seal 15 of refractory material at the top of the furnace to be provided with a receiving hopper 16 in which the solid fuel pieces to be dry distilled are charged for travel through the retort.

The distillation process depends upon subjection of the fuel pieces in the retorts to sufficient heat to effect preheating, degassing and distillation during their travel through the retorts and before passing out of a distillation zone spaced a distance above the bottom of each retort, and consequently before reaching the fuel bed. Such heat is supplied by burning the residue coke on the bed 13.

The combustion gases emanating from the fuel bed are withdrawn from the top of the furnace through one or more outlet ports 17 communicating with the combustion gas discharge duct 18 exteriorly of the furnace which usually leads to a stack or any other suitable draft producing means capable of drawing the combustion gases out of the shaft 11.

The combustion gas comes into intimate contact with the exterior walls of the retorts as the gases pass upwardly in the substantially restricted passages between the walls of the retorts and the inside walls of the furnace to effect heating of the retorts and the fuel therein to the temperatures necessary to produce degassing and distillation.

The distillation gas produced within the retorts is drawn off through ducts 19 extending centrally down through the retorts from their open tops and having their mouths 23 opening to the interior of the retorts at a fixed distance above the combustion zone defined by the upper por-

tions of the fuel bed, and in the distillation zones near the bottom thereof. These ducts lead to a distillation gas collecting duct 21 maintained under a constant sub-atmospheric pressure as by means of a suction pump (not shown).

Air for supporting combustion of the residue coke is fed through the fuel bed from below and to assure an adequate air supply for combustion, the ash pit indicated by the numeral 22 is preferably maintained at an above atmospheric pressure so as to constitute a plenum chamber. Obviously, the plenum chamber 22 may constitute the entire basement room in which the ash pit is located, but in either event, it is important that the pressure of the air be so adjusted with relation to the size of the fuel pieces being treated and the resistance which a bed of such fuel offers to the flow of air therethrough under constant stack draft conditions as to avoid excesses of air which lead to incomplete combustion and cooling of the fuel bed.

Positive assurance against such excesses of air which were found so objectionable in the past is had in the present invention by the maintenance of a constant differential in pressure above and below the fuel bed, which differential may be adjusted with fuel beds of different character to always cause the correct supply of air through the bed for optimum combustion conditions.

Combustion under near ideal conditions is only had, therefore, when certain above atmospheric pressure conditions exist in the plenum chamber 22, and certain conditions of less or sub-atmospheric pressures exist within the furnace shaft 11 to establish a predetermined constant differential in pressure above and beneath the fuel bed for any one size or type of fuel employed. Obviously, under such conditions, it will be apparent that all of the heat energy available in the fuel being burned is utilized to the fullest extent.

While this results in faster and complete combustion, as distinguished from past distillation processes, it produces temperatures in the fuel bed well above the sintering temperature of the fuel, but as will be described hereinafter, sintering is precluded notwithstanding these higher temperatures.

The lower portion of each retort below the distillation zone provides a neutral zone 24 through which fuel leaving the distillation zone must pass to reach the top of the fuel bed where combustion of the degassed fuel, or residue coke, begins. A balance between the low or sub-atmospheric pressures of the combustion gases in the shaft 11 and the distillation gases within the "draw-off" equipment therefor must be maintained within this neutral zone 24. In other words, the mouth 23 of each of the withdrawal ducts 19 must be located in the distillation zone of its retort, but a distance above the zone 24 of pressure balance so as to assure separate withdrawal of the combustion and distillation gases from the furnace without admixture of either with the other.

The elevation of the actual area of zero pressure differential in the zone 24 above the fuel bed is determined for the most part by the magnitude of the pressures of the combustion and distillation gases, and for this reason was subject to wide variation in elevation in past processes brought about especially by change in the combustion gas pressure in the shaft.

In past distillation apparatus, it was necessary, therefore, to have retorts and furnaces of great height or to provide for longitudinal adjustment of the distillation gas withdrawal ducts in their

retorts to enable positioning of the mouths of the ducts a distance above said areas of zero pressure differential.

One of the objects of the present invention, however, is to maintain the areas of zero pressure differential spaced from and at substantially fixed elevations between the distillation zones and the fuel bed so as to obviate the necessity for frequent adjustments of the withdrawal ducts and to enable foreshortening of the retorts and reduction in overall height of the apparatus.

This is accomplished by means of continuously comparing and balancing combustion and distillation gas pressures, detected at locations outside of the neutral zones 24 and which may be remote from these neutral zones, through the medium of a pressure sensitive element 25 and a valve-like damper 26 in the exhaust gas duct 13 controlled by the pressure sensitive element 25.

The combustion gas pressure obtaining within the shaft 11 at an elevation spaced a distance above the fuel bed is impressed on one side of the pressure sensitive element 25 through a tube 27, while the pressure of the distillation gas within the header 20 is impressed on the opposite side of the pressure sensitive element 25 through a tube 28. Hence, any sustained fluctuation in combustion gas pressure within the shaft 11 produced by changing stack draft conditions and which tends to cause shifting of the areas of zero pressure differential up or down within the neutral zones 24 is reflected in the pressure sensitive element 25 to result in the transmission of electrical pulsations thereby through wiring 29 to a reversing motor 30 of known type drivingly connected with the damper 26 so as to effect an adjustment of the position thereof in the discharge duct 13 in a direction and to a degree such as to return the combustion gas pressure to its desired value.

It is desired to emphasize, therefore, that the pressure sensitive element 25 enables maintenance of the areas of zero pressure differential within the medial portions of the neutral zones 24 and hence at substantially fixed elevations above the fuel bed, and in addition serves to maintain the desired differential in pressure above and below the fuel bed despite changing stack draft conditions which tend to alter the combustion gas pressure within the shaft 11. Thus, air for combustion of the fuel under optimum conditions is assured together with substantial fixation of the areas of zero pressure differential within the neutral zones 24 of the retorts. These conditions, it will be noted, are maintained despite fluctuations in pressures of either the combustion or distillation gases.

As will be readily apparent, the desired differential in pressure above and below the fuel bed may also be maintained by varying the above atmospheric pressure of the air supply at the dictation of the pressure sensitive element 25 to offset any changes in sub-atmospheric combustion gas pressure which might tend to shift the zero pressure differential areas within the zones 24.

The location of the zero pressure differential areas within the zones 24 enables substantial reduction in the height of the apparatus, while the maintenance of optimum conditions of combustion to utilize all of the heat energy available in the fuel being burned assures preheating, degassing, and distillation of the materials being treated in such retorts of less height.

As stated, speeding the distillation process by the application of additional heat to the fuel being treated was impossible with past dry distillation apparatus because of the excesses of air, steam, or inert gas employed to cool the fuel bed below the sintering temperature of the fuel. When the fuel bed is cooled in this manner, prevention of sintering is accomplished at the expense of the loss of considerable heat energy.

In past distillation processes the large percentage of excess air contained in the combustion gases results in inefficient combustion, excessive power consumption to remove the excessively large quantity of combustion gas and a substantially slow distillation.

Moreover, the solid fuels which are suitable for dry distillation usually have low sintering temperatures, and high combustion rates are out of the question.

20 The present invention provides for cooling of the fuel bed to effectively prevent sintering of the fuel in a manner enabling optimum conditions of combustion to be maintained in the apparatus so as to speed the distillation process. Optimum 25 conditions of combustion and high speed distillation is made possible by ducts 31 extending inside the fuel bed and provided with a number of branches 32 extending vertically down into the fuel bed towards the grate structure 12 and upwardly into the open bottoms of the retorts. The ducts 31 lead outwardly of the furnace as illustrated to be connected with a source of a fluid heat absorbing medium such as water, steam or a combination of both adapted to be circulated 35 therethrough.

When substantially uniformly distributed throughout the fuel bed the ducts 31 exert a cooling influence throughout the entire bed to cool the same beneath the sintering temperature of the fuel. Obviously, the extent to which the fuel bed is cooled may be readily determined by regulating the amount and temperature of the heat absorbing medium circulated through the ducts.

Since the cooling ducts and their branches in 45 nowise interfere with proper and efficient combustion of the fuel, it will be apparent that the fuel may be efficiently and completely burned, without sintering, at a maximum rate to produce combustion gases of maximum temperature for 50 degassing and distillation of the fuel at higher rates than were hitherto possible.

In equipment formerly used for dry distillation, cracking of the distillation gas and the formation of encrustations in the lower part of the suction tube 19 frequently occurred because of the insufficient cooling effect of the steam, air or inert gas used for prevention of sintering.

The upwardly extending branches 32 of the fluid cooled ducts extend into the open bottoms 60 of the retorts so as to effectively cool the lower portions of the retorts to reduce the risk of cracking and the formation of encrustations. Further assurance against cracking of the distillation gases and the formation of encrustations is had 65 through the provision of jackets 35 surrounding the lower portion of the distillation gas withdrawal ducts 19, as indicated in Figure 8, and through which a fluid heat absorbing medium is adapted to be circulated. The distillation gases, therefore, come into contact with wall surfaces 70 of the distillation gas withdrawal ducts that have been cooled at their portions closest to the combustion zone and which become excessively heated thereby. A covering of insulating material 36 encircling the jackets prevents cooling of the fuel 75

pieces passing through the retort in a manner which might retard the distillation process.

It will be noted that the lower end portions of the retorts 14 are directly above the fuel bed and close to the combustion zone. These bottom portions of the retorts thus are subjected to excessively high temperatures.

Previously expensive heat resistant alloys were used in the construction of the retorts so as to avoid the frequent replacement encountered when ordinary and inexpensive materials were used.

The present invention enables the retorts to be made of inexpensive ordinary metals inasmuch as protection for the lower end portions thereof is afforded by means of fluid cooled ducts 38 and 39 encircling the lower end portions of the retorts in contact with the walls thereof to prevent overheating of the same.

The cooling of the fuel bed and the retorts and their withdrawal tubes by ducts through which a heat absorbing medium such as water is circulated is highly advantageous for another reason aside from speeding distillation. These ducts enable the excess heat removed from the apparatus to be used for useful steam generating purposes, while in the past the excess heat was largely wasted.

Ordinarily the temperature of the fuel bed may be controlled to effectively prevent sintering of the fuel by regulation of the circulation of fluid through the ducts. In some instances, however, it may be desirable to avoid direct contact of the fuel with the cooled walls of the ducts in a manner which might result in undesirable cooling of the fuel pieces closest to the ducts to below the temperature required for combustion.

In such instances the branches 32 of the ducts may be surrounded by shells 40 of metal or insulating material, as shown in Figure 5, which reach temperatures between that of the fuel bed itself and the temperature of the fluid heat absorbing medium circulated through the ducts so as to prevent excessive cooling of the fuel pieces in contact therewith. Preferably, the shells 40 are spaced from the branches 32 as shown so as to provide an air space between the inner walls of the shells and the exteriors of the branches.

When desired, more uniform cooling of the fuel bed may be obtained by providing the branches 32 of the ducts with vertical vanes 41 extending substantially radially from the branches, as shown in Figure 6.

Longitudinal fins 42 both exteriorly and interiorly of the retorts 14 may be provided, as illustrated in Figure 7, to increase the surface area of the retort so as to enable the same to absorb more of the heat of the combustion gases passing therover and to enable such heat to be distributed well into the interior of the retort for substantially uniform heating of the fuel passing therethrough.

It will be appreciated that the distillation apparatus of Figure 1 is readily capable of being employed in parallel groups or batteries such as illustrated in Figures 3 and 4. In this instance, the retorts 45 are of substantially rectangular shape and have a number of substantially equi-spaced distillation gas withdrawal ducts 46 disposed therein with the combustion gases withdrawn through the substantially rectangular space 47 surrounding the retorts and through substantially rectangular passages 48 disposed between adjacent pairs of withdrawal ducts 46.

A number of such retorts located in substan-

tially cellular rectangular shafts or furnace units are arranged in rows to provide groups or batteries 49 and a number of such batteries 49 may be positioned in rows at opposite sides of a common distillation gas withdrawal duct 50 leading to the inlet of a suction pump 51. Each battery of distillation units has its distillation gas withdrawal ducts connected with the common conduit 50 by means of a header 52 and each of the individual furnaces is connected with a combustion gas header 53 having a valve-like damper 26 situated therein for withdrawing the combustion gases and controlling the rate of their withdrawal respectively.

Pressure sensitive elements 25 responding to the pressures of the distillation gases in the headers 52 and to the combustion gases in the individual furnaces are likewise employed to automatically maintain the areas of substantially zero pressure differential in the retorts at fixed elevations but spaced above the combustion zone and below the mouths of the distillation gas withdrawal ducts as previously explained.

Each row of batteries has its combustion gas discharge duct 53 leading to a main smoke-gas duct 55 which in turn is adapted to be connected with a stack or suction pump to effect withdrawal of the combustion gases from the individual furnaces.

From the foregoing description taken in connection with the accompanying drawings it will be readily apparent to those skilled in the art that this invention provides an improved process for dry distilling solid fuel at rates higher than hitherto possible, and which enables the overall height of the apparatus for carrying out the process to be materially reduced to effect not only a saving in space but cost as well.

What we claim as our invention is:

1. In a dry distillation apparatus of the character described wherein solid fuel is fed through a retort heated exteriorly by hot combustion gases emanating from a fuel bed upon which degassed fuel discharging from the retort is deposited and burned, and wherein the rate and efficiency of combustion of the degassed fuel determines the speed of the distillation process and depends upon the differential in pressure between combustion gas above the fuel bed and combustion air fed to the fuel bed from below: duct means for withdrawing combustion gases from the furnace after passage of the combustion gases over the retort to degas and distill fuel therein, said duct means being connected with a source of suction whereby sub-atmospheric pressure conditions obtain within the furnace above the fuel bed and within the discharge end of the retort; means providing a supply of combustion air below the fuel bed at a pressure of such magnitude with respect to the sub-atmospheric pressure obtaining above the fuel bed as to establish a predetermined differential between the pressures obtaining above and below the fuel bed at which combustion air is fed through the fuel bed at a rate to support combustion under optimum conditions; other duct means having its mouth opening to the interior of the retort near the discharge end thereof for withdrawing distillation gases from the retort, said other duct means being connected with a source of sub-atmospheric pressure of a magnitude so related to the sub-atmospheric pressure in the furnace as to create a zone of balance between the pressures of combustion and distillation gases within the retort at a location be-

tween and spaced from the mouth of the distillation gas withdrawal duct and the discharge end of the retort so as to preclude withdrawal of the combustion gases with the distillation gases and vice versa; and means for regulating the pressure at one side of the fuel bed by reference to the relationship between the pressures of combustion and distillation gases measured at points remote from said zone of balance so as to at all times maintain said zone of pressure balance at said location and also maintain substantially said predetermined differential in pressure above and below the fuel bed to assure burning of the fuel under optimum conditions of combustion.

2. A distillation furnace as set forth in claim 1 including fluid cooled duct means entering the furnace to be embedded in the bed of burning fuel adapted to circulate sufficient coolant through said fuel, in heat exchange relation but out of contact therewith, for carrying away enough heat therefrom to preclude sintering of the fuel and thereby permit burning of the fuel under optimum conditions of combustion.

3. A distillation furnace as set forth in claim 1 including a fluid cooled jacket on the duct means for the distillation gas for precluding heating of the distillation gas passing therethrough to excessively high temperatures.

4. A distillation furnace as set forth in claim 1 including a fluid cooled jacket on the duct means for the distillation gas for precluding heating of the distillation gas passing therethrough to excessively high temperatures; and heat insulation interposed between the fluid cooled jacket on the duct means for distillation gas and the fuel in the retort to prevent undesirable cooling of the fuel processed in the retort.

5. A distillation furnace as set forth in claim 1 including fluid cooled means on the discharge end of the retort which is subjected to the intense heat of the burning fuel bed for cooling said discharge end of the retort to thereby enable the retort to be constructed from inexpensive materials ordinarily damaged by intense heat.

6. In a dry distillation apparatus of the character described wherein solid fuel is fed through a retort heated exteriorly by hot combustion gases emanating from a fuel bed upon which degassed fuel discharging from the retort is deposited and burned, and wherein the rate and efficiency of combustion of the degassed fuel determines the speed of the distillation process and depends upon the differential in pressure between combustion gas above the fuel bed and combustion air fed to the fuel bed from below: duct means for withdrawing combustion gases from the furnace after passage of the combustion gases over the retort to effect degassing and distillation of fuel therein, said duct means being connected with a source of suction whereby sub-atmospheric pressure conditions obtain within the furnace above the fuel bed and within the discharge end of the retort; means providing a supply of combustion air below the fuel bed at a substantially uniform pressure; a regulator in said duct means for adjusting the sub-atmospheric pressure obtaining within the furnace and by which a differential in pressure above and below the fuel bed of predetermined magnitude may be established at which combustion air flows through the fuel bed in quantities assuring burning of the fuel under optimum conditions of combustion; a distillation gas withdrawal duct having its mouth opening to the interior of the retort near the discharge end thereof for withdrawing

distillation gases from the retort, said withdrawal duct being connected with a source of substantially uniform sub-atmospheric pressure of a magnitude so related to the sub-atmospheric pressure obtaining in the furnace as to create a zone of balance between said sub-atmospheric pressures of the combustion and distillation gases so as to preclude withdrawal of combustion gases with the distillation gases and vice versa, said zone of balanced pressure within the retort being subject to shifting upon change in the sub-atmospheric pressure obtaining within the furnace; and a pressure sensitive element for comparing the pressures of combustion and distillation gases measured at points remote from said zone of balanced pressure and operable upon change in the relation of said pressures to effect adjustment of the regulator in said duct means to maintain said zone of pressure balance at a location between and spaced from the mouth of the distillation gas withdrawal duct and the discharge end of the retort.

7. A distillation furnace as set forth in claim 6 including fluid cooled duct means entering the furnace to be embedded in the bed of burning fuel and adapted to have enough fluid coolant circulating therethrough for carrying away sufficient heat to preclude sintering of the fuel and thereby permit burning of the fuel under optimum conditions of combustion.

8. A distillation furnace as set forth in claim 1 including fluid cooled duct means entering the furnace to be embedded within and distributed throughout the bed of burning fuel for absorbing sufficient heat therefrom to preclude sintering of the fuel and to thereby enable burning of the fuel under optimum conditions of combustion; and heat insulating means for said fluid cooled duct means to prevent excessive cooling of the fuel nearest the fluid cooled duct means.

9. A distillation furnace as set forth in claim 1 including heat-absorbing surfaces on the exterior of the retort for improving heat transfer between the hot combustion gases contacting the exterior of the retort and the fuel inside the retort.

10. A distillation furnace as set forth in claim 1 including heat absorbing surfaces on the exterior of the retort for improving heat transfer between the hot combustion gases contacting the exterior of the retort; and heat dissipating surfaces on the interior of the retort for carrying the heat thereof into the interior of the body of fuel being fed through the retort to facilitate heating thereof.

11. A distillation furnace as set forth in claim 1 including fluid cooled duct means entering the furnace to be embedded within and distributed throughout the bed of burning fuel for absorbing sufficient heat therefrom to preclude sintering of the fuel and to thereby enable burning of the fuel under optimum conditions of combustion; and means encircling portions of the fluid cooled duct means in spaced relation thereto to provide an air space between the encircled portions of the fluid cooled duct means and the directly adjacent fuel pieces to preclude excessive cooling thereof.

12. A distillation furnace as set forth in claim 1 including fluid cooled duct means entering the furnace to be embedded within the bed of burning fuel for absorbing sufficient heat therefrom to preclude sintering of the fuel and to thereby enable burning of the fuel under optimum conditions of combustion; and fins on portions of said fluid cooled duct means extending

outwardly therefrom into the fuel bed to absorb heat from areas thereof spaced from said portions of the fluid cooled duct means so that cooling of the fuel bed is not restricted to areas immediately adjacent to said portions of the fluid cooled duct means whereby the fuel bed is substantially uniformly cooled by said finned portions of the fluid cooled duct means.

13. The method of dry distilling solid fuel which involves feeding the fuel to a distillation zone defined by an upright duct open at its bottom and contained within a shaft, distilling the fuel in said zone, feeding degassed fuel through a neutral zone in the lower portion of the upright duct to a combustion zone in the lower portion of the shaft surrounding the duct and in open communication with the distillation zone through said neutral zone, burning the degassed fuel in a bed in said combustion zone, and passing the hot combustion gases resulting from such burning of the degassed fuel upwardly through the shaft in indirect heat exchange relation with the fuel in the duct to effect distillation of said fuel, which method is characterized by the steps of: withdrawing the distillation gases from the distillation zone; exhausting the combustion gases after the same have been passed in indirect heat exchange relation with the fuel in the distillation zone; supplying primary combustion air to the fuel in the combustion zone; detecting the pressure of the combustion gases leaving the combustion zone, at a point outside the neutral zone; detecting the pressure of the distillation gases leaving the distillation zone, at a point outside the neutral zone; automatically comparing these two pressures; and regulating the pressure at the combustion zone in accordance with the differential between said two detected pressures to at all times maintain a zero differential between the pressure of the gases in said neutral zone in an area thereof as close as possible to the medial portion of the neutral zone to preclude combustion gases being withdrawn with the distillation gases and vice versa.

14. The method defined in claim 13 further characterized by the steps of: preliminarily adjusting the pressures in the combustion and distillation zones to produce an area of zero pressure differential in said neutral zone, which area tends to fluctuate back and forth between the distillation and combustion zones in consequence to changes in pressure in the combustion and distillation zones; detecting the pressure of the gases leaving the combustion zone, at a point outside the neutral zone; detecting the pressure of the distillation gases leaving the distillation zone, at a point outside the neutral zone; automatically comparing these two pressures; and regulating the pressure at the combustion zone proportionately to the degree of deviation from the pressure differential indicated by said comparison when the area of zero pressure differential is adequately spaced from the distillation and combustion zones, to restore said differential and thereby maintain said area of zero pressure differential adequately spaced from the distillation and combustion zones.

15. The method of dry distilling solid fuel which involves feeding the fuel into the top of a distillation zone defined by an upright duct open at its bottom, distilling the fuel in said zone, feed-

ing degassed fuel through a neutral zone in the bottom portion of the upright duct to a combustion zone in the bottom of a shaft surrounding the duct and in open communication with the distillation zone through the neutral zone, burning the degassed fuel in a bed in said combustion zone, and passing the hot combustion gases resulting from such burning of the degassed fuel upwardly through the shaft in indirect heat exchange relation with the fuel in the duct to effect distillation of the fuel therein, which method is characterized by the steps of: withdrawing the distillation gases from near the bottom of the duct which defines the distillation zone; exhausting the combustion gases from the shaft after the same have been passed in indirect heat exchange relation with the fuel in the distillation zone; supplying primary combustion air to the burning fuel in the combustion zone at a pressure higher than that of the combustion gases leaving the combustion zone; measuring the pressure of the combustion gases leaving the combustion zone at a point outside the neutral zone; measuring the pressure of the distillation gases leaving the distillation zone, at a point outside the neutral zone; automatically comparing these two pressures; regulating the pressure at the combustion zone in accordance with the differential between said two measured pressures to establish an area of zero pressure differential within said neutral zone to restrict said area of zero pressure differential to a relatively small range of fluctuation in the medial portion of the neutral zone so as to preclude combustion gases being withdrawn with the distillation gases and vice versa, and to also maintain a predetermined differential in pressure across the combustion zone which induces combustion of the fuel in said zone at a rate greater than that which causes sintering of the fuel; and cooling the fuel in the combustion zone by passing a heat absorbing and dissipating medium in indirect heat exchange relation with all portions of the fuel in the combustion zone and in quantities sufficient to permit combustion of the fuel at said greater rate without danger of sintering.
